Attorney

UNITED STATES PATENT OFFICE.

CHARLES G. MARTINDALE, OF SCOTIA, CALIFORNIA.

PIPE-WRENCH.

1,335,252.

Specification of Letters Patent. Patented Mar. 30, 1920.

Application filed January 15, 1919. Serial No. 271,245.

To all whom it may concern:

Be it known that I, CHARLES G. MARTINDALE, a citizen of the United States, residing at Scotia, in the county of Humboldt and State of California, have invented certain new and useful Improvements in Pipe-Wrenches, of which the following is a specification, reference being had to the accompanying drawings.

10 This invention relates to certain improvements in pipe wrenches, and it is an object of the invention to provide a device of this character having novel and improved means whereby an effective grip is had upon the pipe when pull is imposed upon the handle.

15 It is also an object of the invention to provide an improved wrench of this general character comprising two relatively movable jaws together with means whereby 20 said jaws may be held in their relative positions.

25 The invention consists in the details of construction and in the combination and arrangement of the several parts of my improved pipe wrench whereby certain important advantages are attained and the device rendered simpler, less expensive and otherwise more convenient and advantageous for use, as will be hereinafter more fully set forth.

30 The novel features of my invention will hereinafter be definitely claimed.

35 In order that my invention may be the better understood, I will now proceed to describe the same with reference to the accompanying drawings, wherein:

40 Figure 1 is an elevational view of a wrench constructed in accordance with an embodiment of my invention, with a portion broken away; and

45 Fig. 2 is a fragmentary view in elevation of my improved wrench as herein embodied with certain of the parts in a second position.

50 As disclosed in the accompanying drawings, 1 denotes an elongated shank having its outer end portion serving as a handle while its opposite end portion is provided with a rigid jaw 2. The inner edge face 55 of the shank 1 from the end provided with the jaw 2 to a point substantially midway of said shank is provided with a rack 3 with which engages the toothed edge face of a supplemental shank 4.

55 The shank 4 also extends between a pair of rearwardly directed plates carried by the

shank 1 adjacent the jaw 2, and said plates are of a length to extend rearwardly of the supplemental shank 4.

Pivottally supported between the extended 60 portions of the plates 5 is an eccentric or cam 6 provided with an operating lever 7. The lever 7 is of a length to extend beyond the inner sides of the plates 5.

The high point α of the eccentric or cam 65 6 is so positioned that when the lever is moved inwardly toward the supplemental shank 4, said supplemental shank will be effectively locked to the shank 1 against movement longitudinally of the shank 1. 70 When the lever 7 is moved in the opposite direction, the high point α is so positioned as to permit the shank 4 to be readily moved longitudinally of the shank 1.

The outer end portion of the supplemental 75 shank 4 is provided at its inner side with a longitudinally directed extension 8 having its outer face 9 serving as a cam or eccentric.

10 denotes a swinging jaw coacting with the jaw 2 and carried by the outer end of 80 the supplemental shank 4. Said jaw 10 is hingedly connected as at 11 with the extension 9 and is provided with an inwardly disposed tail or extension 12 provided with a cam or eccentric face 14 engaging the 85 eccentric or cam face 9 of the extension 8.

As is clearly disclosed in the accompanying drawings, it will be self evident that when the jaws 2 and 10 are engaged with the work and pull is imposed on the outer 90 or handle portion, the eccentric or cam faces 9 and 14 will coact in a manner to swing the jaw 10 inwardly toward the jaw 1 so that an effective grip of said jaws upon the pipe or other work is assured, so that the 95 greater the pull upon the outer or handle end portion of the shank 1, the tighter the grip of the jaws 2 and 10 will be upon the work.

From the foregoing description, it is 100 thought to be obvious that a pipe wrench constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as 105 limiting myself to the precise arrangement and formation of the several parts herein 110

shown in carrying out my invention in practice except as hereinafter claimed.

I claim:

1. A wrench of the character described comprising a shank provided with a jaw, a supplemental shank coacting with the first named shank, a jaw hingedly connected with the supplemental shank and coacting with the jaw of the first named shank, said supplemental shank and second jaw being provided with coacting cam faces whereby said second jaw is caused to swing toward the first named jaw when pull is imposed upon the first named shank and when the first named jaws are engaged with the work.
2. A wrench of the character described comprising a shank provided with a jaw, a supplemental shank coacting with the first named shank, a jaw hingedly connected with the supplemental shank and coacting with a jaw of the first named shank, said supplemental shank and second jaw being provided with coacting cam faces whereby said second jaw is caused to swing toward the first named jaw when pull is imposed upon the first named shank and when the first named jaws are engaged with the work.

upon the first named shank and when the first named jaws are engaged with the work, said first named shank and supplemental shank being relatively adjustable, and means for holding the same against relative movement.

3. A wrench of the character described comprising a shank provided with a jaw, a supplemental shank coacting with the first named shank, a jaw pivotally connected with the supplemental shank and coacting with the jaw of the first named shank, said supplemental shank and second jaw in close proximity to the pivotal connection therebetween being provided with coacting cam faces whereby said second jaw is caused to swing toward the first named jaw when pull is imposed upon the first named shank and when the jaws are engaged with the work.

In testimony whereof I hereunto affix my signature in the presence of two witnesses.

CHARLES G. MARTINDALE.

Witnesses:

AL. I. RICHLIN,
F. L. KEHOE.
